UNITED STATES PATENT OFFICE.

JAMES W. POFF, OF HARRISBURG, ARKANSAS.

SAWING-MACHINE.

SPECIFICATION forming part of Letters Patent No. 311,675, dated February 3, 1885.

Application filed November 18, 1884. (No model.)

To all whom it may concern:

Be it known that I, JAMES W. POFF, of Harrisburg, in the county of Poinsett and State of Arkansas, have invented a new and Improved Sawing Machine, of which the following is a full, clear, and exact description.

The object of my invention is to provide a simple, inexpensive, efficient, and durable one-man crosscut-sawing machine which may be worked by utilizing the weight of the operator, and with an easy natural swing of the body, causing little fatigue.

The invention consists of the combinations of parts and their construction, substantially as hereinafter fully set forth and claimed.

Reference is to be had to the accompanying drawing, forming a part of this specification, and which is a perspective view of my improved sawing-machine as in use.

20 The letters A B indicate, respectively, the top and legs of a strong bench-like frame adapted to support the working parts of the machine. The top A has a central opening, *a*, and has fixed to its forward end the vertical strut or post C, which preferably is forked at its lower end, where it connects pivotally at *c* with the forward ends of two parallel bars, *d d*, which, with their rear connecting foot piece or plate, D', form the treadle D of the machine.

30 Within the opening *a* of the top A, I pivot on a strong pin, *e*, the cross-head E, which connects rigidly with a pendent lever, F, which in turn connects pivotally at *g* with the head-piece G, to which the saw H is rigidly connected at *h*.

On the rear end of the cross-head E is formed a hook, I, to receive the upper end or cross-bar of a Ω -shaped stirrup or link, J, the lower ends, *j j*, of which are bent to enter loosely 40 the bars *d d* of the treadle D, and the forward end of the cross-head E connects pivotally at *k* with the lower forked end of a link, K, the upper end of which is pivoted at *l* in the forked end of the hand-lever L, which is pivoted at *m* to the upper end of the post C. The hand-lever has a suitable cross-bar, M, at the rear end, by which it may be grasped and worked conveniently.

The operation is as follows: The log, O, to be

sawed or cross-cut is rolled to the front of the 50 machine, or the machine is placed behind the log, as shown, which may easily be done, and so that the saw H crosses the top of the log at the desired place. The operator now stands on the treadle-plate D' and grasps the handle 55 M of the lever L, and by bearing his weight mainly on the plate D' the saw H will be carried forward into the log, and by next bearing his weight mainly on the handle M of lever L the saw will be carried back again, and these 60 movements may alternately and rapidly be continued to give successive forward and back strokes to the saw until the log is cut through. The link J connects to the treadle D back of the center of the treadle, and the link connects 65 with the cross-head E much nearer its pivot *e* than does the link K, pivoted to the handle, so that the downward bodily movement of the operator with the treadle-plate D' is not very great to give a long and rapid forward stroke 70 to the saw, while the handle M of the lever L has considerable range of movement, whereby the operator may work the machine steadily with an easy swing of the body.

With my improved machine one man can 75 do quite double the work he can do by driving a saw by hand-power alone.

I propose to make all parts of the machine except the bench of suitable cast or wrought metal, so it shall be cheap and durable. 80

Having thus described my invention, what I claim as new, and desire to secure by Letters Patent, is—

The combination, with the fixed upright equidistantly secured to the supporting-frame, 85 of the pendent lever having a fixed cross-head, with one arm connected by links to a treadle, one end of said treadle being connected to the lower end of said fixed upright, and the hand-lever, pivoted at one end to the upper end of 90 the said upright, and connected intermediately of its pivoted and free ends by a link to the other arm of said cross-head, substantially as and for the purpose set forth.

JAMES W. POFF.
